SCRIBING TOOL

Howard V. Neiss, Lancaster, Pa., assignor to Armstrong Cork Company, Lancaster, Pa., a corporation of Pennsylvania

Application March 27, 1947, Serial No. 737,491

5 Claims. (Cl. 33—41)

1

My invention relates to a scribing tool and, more particularly, to a tool which is useful in the installation of linoleum and other surface coverings.

It is an object of this invention to provide a scribing tool for use in connection with the installation of surface covering wherein it is desired to scribe a line or lines from a surface disposed a substantial distance above the plane of the surface covering.

A further object of the invention is to provide a scribing tool adapted to scribe or cut one or a plurality of lines scribed from a surface having a geometrical outline different from the outline at the surface of the covering.

Another object of my invention is to provide a scribing tool having multiple scribing points which may be readily adjusted in use without changing the initial and precise setting of the scribing points.

A still further object of my invention is to provide a scribing tool which will scribe from a surface substantially above the plane of the scribing point and which is provided with an adjustable support which will prevent tilting of the tool in use.

In the installation of linoleum floor coverings, it is common practice to insert a so-called feature strip of a color contrasting with the color of the main floor covering, the strip being spaced from the wall surfaces and from cabinet surfaces which may project into the room. In kitchens, cabinets are frequently built in which project into the room and which have rounded ends so as to provide an attractive appearance and eliminate sharp corners. These cabinets are generally provided with recessed kick boards which are rectangular and do not follow the contour of the curved end of the cabinet. In installing linoleum in a kitchen including such a projecting cabinet where the floor covering includes a feature strip or a border or both, common practice is to have the feature strip spaced from the main cabinet surfaces a uniform distance and to provide a curvature in the feature strip or border corresponding to the curvature of the cabinet. The same is true in the installation of floor coverings around bars in game rooms, public places, and the like. Similar constructions are employed for store counters, island display cabinets, and the like, and the same practice is followed in the installation of floor coverings in such areas.

With such constructions, the scribing tools now on the market cannot be used to scribe the surface covering along a line following the contour

2

of the cabinet, for the guiding surface of the scribing tool lies in substantially the same plane as the plane of the upper surface of the covering, and since recessed toe boards are provided and the surface from which a line is to be scribed is disposed three or four inches above the floor surface, the scribing tools now available are not useful for the purpose.

According to the present invention, I provide 10 a scribing device which comprises a frame having an opening in it which receives a scribe block. Scribing means are mounted in the block and extend through the opening to a position below the frame. The frame is provided with a 15 vertical extension adjacent one end thereof which projects above the frame and is provided with a guide which is adapted to engage the surface from which a line is to be scribed. In use, the tool is placed on the surface covering with the 20 scribing or cutting point in engagement with the covering and with the guide on the extension lying in engagement with the surface of the cabinet from which a line is to be scribed. The tool is held firmly against the cabinet, and a 25 line is scribed or cut in the surface covering by moving the tool around the cabinet.

In order that the invention may be more readily understood, I shall describe the same in conjunction with the attached drawing in which:

30 Figure 1 is a side elevation illustrating a preferred embodiment of my invention;

Figure 2 is a top plan view of the tool shown in Figure 1;

Figure 3 is a sectional view taken on the line

35 III—III of Figure 1; and

Figure 4 is a perspective view illustrating a use of the device in the scribing or cutting of a floor covering.

Referring to Figures 1 and 2, the scribe includes a frame 2 having a longitudinal opening 3 therein. The frame 2 is preferably rounded at its forward end, as indicated at 4. A block 5 is fastened to the frame 2 by suitable means, such as the rivets indicated at 6 and 7. The block 5 may be welded to the frame 2 or may be otherwise secured. The block 5 and the frame 2 are drilled, as indicated by the dotted lines at 8 in Figure 1, and a set screw 9 is provided in the block 5. A vertical extension 10 is provided which is adapted to pass through the opening 3 and is held in adjusted position by means of the set screw 9 clamping against a flat surface 11 provided on the extension 10.

The extension 10 has a coupling 12 secured to it by suitable means, such as welding, brazing,

frictional fitting, or the like. The coupling 12 is provided with an opening indicated by the dotted lines at 13 in Figure 1, the axis of the opening 13 lying substantially parallel to the length of the frame 2. A guide 14 is received within the opening 13 and is clamped in place by a set screw 15. A flat 16 is provided on the guide member 14, and this insures that the guide member, when clamped in position, will lie in proper relationship with respect to the extension 10 and the frame 2. The guide member 14 is capable of limited adjustment within the opening 13 in a horizontal direction parallel to the length of the frame 2.

A scribe or knife holder generally indicated by the numeral 17 is provided and is adjustably secured to the frame 2 in the manner best illustrated in Figure 3. The frame 2 is recessed on its lower surface, as indicated by the numeral 18. The holder body 19 is provided with a rectangular extension 20 of a width corresponding to the width of the slotted opening 3 so as to maintain the holder 17 in proper alignment with respect to the frame 2. The holder is movable along the slot 3 and is capable of being locked in adjusted position by means of a locking pin 21 which has a rectangular head 22 which fits into the recess 18 on the under side of the frame 2. The pin 21 is threaded, and a wing nut 23 clamps the holder 17 to the frame 2 through the opening 3.

A scribing or cutting member 24 (Figure 2) is carried by the holder 17 and is received within a dove-tailed opening 25 which extends vertically throughout the length of the holder 17. The knife or scribing point 24 is locked into position by means of two screws 26, one of which can be seen in Figure 2, the second screw being disposed therebelow.

Figure 4 shows a typical floor covering installation in which the scribing device of the present invention may be used. There is shown in Figure 4 a cabinet 27 which projects into the room and is provided with a curved end 28. The lower portion of the cabinet is recessed to provide a kick board 29 which is generally rectangular, as indicated in Figure 4. It is desired in this installation to inset a feature strip in the area 30, such feature strip to correspond in curvature to the curvature of the end 28 of the cabinet 27. In the embodiment illustrated in Figure 4, I have shown two cutting or scribing holders so that both lines 31 and 32 for the reception of the curved feature strip may be simultaneously scribed or cut. It is obvious that the lines may be scribed separately, but this requires two separate scribing operations, and there is always the possibility that the tool may not be moved in precisely the same path, making it difficult to obtain a good fit of the piece to be inserted. In some instances, of course, it will be necessary to only scribe a single line, for instance, where a border is to be used which will have a curvature corresponding to the curvature 28 of the cabinet 27.

In the use of my scribing device, as illustrated in Figure 4, the scribing points 24 for forming the lines 31 and 32 will be adjusted vertically through the opening 3 to a proper position and clamped in such position by the screws 26 shown in Figure 2. The extension 10 will then be adjusted to a position where the end 33 thereof will lie in engagement with the upper surface of the covering 34 to be scribed so as to maintain the frame 2 substantially parallel to the covering 34 when the scribing points have penetrated to the desired

depth. This is illustrated in Figure 1. It is particularly important to provide proper support for the tool adjacent the extension 10 where the guiding surface 14 is disposed a substantial distance above the frame 2 and tilting of the tool is likely to occur, resulting in an inaccurate scribe line. The guiding member 14 will be brought into engagement with the curved surface 28 of the cabinet 27, and since the guide 14 is bifurcated, as clearly shown in Figure 2, the surfaces 35 and 36 thereof will engage the cabinet and hold the scribing tool in proper position as the same is moved around the cabinet. By providing the flat 11 on the extension 10 and the flat 16 on the guide 14, proper positioning of the guide 14 with respect to the scribing points or cutters is always insured.

By making the guide 14 adjustable in the coupling 12, it is possible to adjust the position of the scribing points or cutters with respect to the surface from which the line is to be scribed without altering the position of the holders 17. This is particularly desirable where two lines are being simultaneously scribed or cut, for adjustment of one of the scribes or cutters would necessitate adjustment of the other in order to maintain the desired spaced relationship between the two which is dependent upon the width of the strip to be inserted. With the adjustable guide member 14, it is possible to fit the holders 17 and the attached scribing points or cutters in the precise spaced relationship desired and in approximately the correct position with respect to the engaging surfaces 35 and 36 of the guide 14 and then make any minor adjustment necessary by merely loosening the locking screw 15 and adjusting the position of the guide 14 in the coupling 12.

In some instances, particularly with relatively thin coverings, the device may be used to sever the material completely. In most instances, however, as in the installation of linoleum, it will be found desirable to merely scribe or cut part way through the covering with the device and cut with a conventional linoleum knife, following the scribed or partially cut lines. In the claims, the device is referred to as a scribing device, and the members which engage the covering are referred to as scribing elements. It is intended by such terminology to include scribing pins, knives, or other elements which penetrate partially or completely through the surface covering or merely mark the upper surface thereof.

While I have illustrated and described a preferred embodiment of my invention and a modification thereof, it will be understood that the same may be otherwise embodied and practiced within the scope of the following claims:

I claim:

1. A scribing device comprising a frame having a longitudinal opening therein, a scribe holder received within said opening, scribing means mounted on said scribe holder and extending through said opening below said frame, a mounting block on said frame adjacent one end thereof, said block and frame having an opening therein directed perpendicular to the frame, a vertical post disposed within said opening and terminating in a supporting surface disposed below said frame for engagement with the covering to be scribed, means for adjustably positioning said post on said frame with said supporting surface so disposed as to obtain substantial parallelism between the surface of the covering and the frame during scribing, and a horizontal guide adjustably attached to said post and having a

portion for engagement with a surface disposed a substantial distance above the covering to be scribed and from which surface a line is to be scribed.

2. A scribing device comprising a frame having a longitudinal opening therein, a scribe holder received within said opening, scribing means mounted on said scribe holder and extending through said opening below said frame and perpendicular thereto, a mounting block on said frame adjacent one end thereof, said block and frame having an opening therein directed perpendicular to the frame, a vertical post disposed within said opening and terminating in a supporting surface disposed below said frame for engagement with the covering to be scribed, means for adjustably positioning said post on said frame with said supporting surface so disposed as to obtain substantial parallelism between the surface of the covering and the frame during scribing to dispose said scribing means perpendicular to the surface to be scribed, said post having an opening therein extending transversely thereof and substantially parallel to the length of said frame, and a horizontal guide disposed within said opening in said post for limited adjustment through said opening, said guide having a portion for engagement with a surface disposed a substantial distance above the covering to be scribed and from which surface a line is to be scribed.

3. A scribing device in accordance with claim 2 in which there are a plurality of holders received within the longitudinal opening in the frame which are independently adjustable therealong, each of said holders having scribing means mounted therein and extending through said opening below said frame, and in which there is means provided for locking the horizontal guide in adjusted position with respect to the holders, whereby the holders may be clamped in adjusted position with respect to one another and the guide adjusted to position the holders with respect to the surface from which the lines are to be scribed.

4. A scribing device for scribing surface coverings from curved surfaces disposed a substantial distance above the surface of the covering to be scribed, said device comprising a frame having a longitudinal slot therein, a scribe holder received in the slot and adjustable therealong, means for clamping the scribe holder to the frame in adjusted position, scribing means adjustably secured to the scribe holder and passing through the slot to a position below the frame, with the scribing means disposed substantially perpendicular to the frame, a mounting block on said frame adjacent one end thereof, said block and frame having an opening therein directed perpendicular to the frame, a vertical post disposed within said opening and terminating in a supporting surface disposed below said

frame and providing a bearing for engagement with the covering to be scribed, means for adjustably positioning said post on said frame with said supporting surface so disposed as to obtain substantial parallelism between the surface of the covering and the frame during scribing to dispose said scribing means perpendicular to the surface of the covering to be scribed, a coupling on said post having an opening therein which extends substantially parallel to the length of the frame, a bifurcated guide received within the opening in said coupling and adjustable therein, means for locking said guide in adjusted position, and spaced surfaces on the arms of said bifurcated guide for engagement with a curved surface disposed a substantial distance above the covering to be scribed and from which curved surface a curved line is to be scribed on the surface covering.

5. A scribing device comprising a frame having a longitudinal opening therein, a scribe holder received within said opening and adjustable therealong, means for clamping the scribe holder to the frame in adjusted position, scribing means adjustably secured to the scribe holder and passing through the opening in the frame and extending therebelow, a mounting block on said frame adjacent one end thereof, said block and frame having an opening therein directed perpendicular to the frame, a vertical post passing through said opening and terminating in a supporting surface disposed below said frame for engagement with the covering to be scribed to adjustably position said frame and obtain substantial parallelism between the surface of the covering and the frame during scribing, said post having a horizontal opening therein, means for locating the post in adjusted position with the hole in the post in alignment with the longitudinal center line of the frame, means for locking the post in adjusted position, a horizontal guide having a bifurcated end, means for locating said guide in a horizontal position within said opening in said post, whereby the guide will have its axis substantially parallel to the frame and in alignment with the longitudinal center line of the frame, and means for locking said guide in position.
